UNITED STATES PATENT OFFICE.

HENRY F. FISHER, OF LOS ANGELES, CALIFORNIA.

SHOULDER-PAD FOR VIOLINS, &c.

1,377,571.

Specification of Letters Patent. Patented May 10, 1921.

Application filed March 30, 1920. Serial No. 369,973.

To all whom it may concern:

Be it known that I, HENRY F. FISHER, a citizen of the United States, residing at Los Angeles, in the county of Los Angeles and 5 State of California, have invented new and useful Improvements in Shoulder-Pads for Violins, &c., of which the following is a specification.

This invention relates to a shoulder pad 10 for correctly cushioning a violin or other musical instrument upon the player's shoulder, and has for its object the provision of a device of this character which will not only provide an effective correct cushioning 15 medium, but which will also form a protection for the player's clothing against excessive wear due to the contact of the instrument.

It is an object of this invention to provide 20 a pad which may be readily placed in, and removed from position upon the player's shoulder, and which includes simple but effective means for retaining the pad in position upon the shoulder.

25 It is a further object of the invention to provide a pad which will be highly resilient and of light weight, the cushioning medium within the pad for this purpose, preferably, being made of the luffa plant; and the pad 30 being so stuffed with the cushioning medium as to retain its original shape for correctly positioning the musical instrument.

Other objects of the invention will be readily understood from the following description of the accompanying drawings in 35 which:

Figure 1 is a perspective view of my improved shoulder pad showing the same in position upon a player's shoulder.

40 Fig. 2 is a similar view showing the manner in which a violin is rested upon the pad.

Fig. 3 is a front plan view of my improved shoulder pad.

Fig. 4 is an end view of the same.

45 Fig. 5 is a transverse section through the pad taken on the line 5—5 of Fig. 3.

Referring to the accompanying drawings, my improved pad is shown as comprising a casing formed of a single piece of material 50 consisting of a front portion 1 having upper and lower continuations thereof as shown at 2 and 3 folded back upon the front portion and meeting at approximately medially of the upper and lower edges of the 55 front portion as shown at 4. The meeting edges of the front portion 1 with the upper

and lower portions 2 and 3 of the rear portion of the casing, and the meeting edge between the upper and lower portions of the rear of the casing, are suitably united as by 60 stitching 5, to form a closed casing. Before the final seam to this casing is stitched, the casing is filled with a suitable cushioning medium or packing 6. This packing may be of any suitable material such as felt, or the 65 like, but in practice I find it desirable to employ a dried vegetable growth, preferably the dried fibrous skeleton of the fruit of the luffa plant, as the packing medium, as by the use of the latter the desired cushioning 70 qualities are obtained and at the same time the weight of the cushioning medium is reduced to a minimum. The material forming the casing of the pad is so shaped, and the cushioning medium is packed therein in 75 such manner, as to form a pad decreasing in thickness from its upper to its lower edge, as clearly shown in Fig. 4. Furthermore, the pad is arranged with its rear surface curved inwardly from its upper to its lower 80 edge, to conform to the contour of a man's shoulder, so that when the pad is rested upon the shoulder it will assume a natural position thereupon. The front surface of the pad may also be curved to any desired 85 degree which will permit of resting the musical instrument thereupon to the best advantage for correctly positioning the latter.

When in use the pad is placed upon the shoulder, either beneath the edge of the 90 coat, or beneath the edge of the vest, and when in such position will form an effective cushioning means, for a musical instrument such as a violin, when the latter is rested upon the shoulder.

95 In order to protect the clothing of the player against wear, due to the contact of the musical instrument when thus supported upon the shoulder, the pad is preferably provided with a protecting strip arranged to be 100 folded over the outside of the player's coat.

Such a strip is shown at 7 as projecting laterally from the edge of the shoulder pad, this strip being a suitable length of any desired material, and preferably of a width 105 approximately equal to one-half the length of the shoulder pad, and projecting from the upper portion of the shoulder pad.

110 In order to retain the shoulder pad in position upon the shoulder of a player, a strip 8 similar to the strip 7, previously described, may be secured to the edge of the

shoulder pad so as to project laterally from the lower portion thereof below strip 7 and parallel thereto when the shoulder pad is placed in position as previously described. 5 This latter strip is adapted to be folded back beneath the edge of an inner garment of the player, either the vest or the shirt, and will thus afford efficient means for retaining the shoulder pad in position. The 10 strips 7 and 8 may be attached to the casing of the shoulder pad in any desired manner, as by the stitching 9.

By the improved shoulder pad as thus described, it will be seen that I provide simple but effective means for cushioning a musical instrument upon a player's shoulder, said cushioning means having associated therewith practical means for retaining the same in operative position, and also 20 including a device for protecting the clothing of the player against wear as a result of contact with the musical instrument when the same is placed in playing position.

It will be apparent that various changes 25 and modifications may be made in the combinations and arrangements of parts herein described, and I therefore do not wish to limit myself to the exact disclosures made herein.

30 What I claim is:

1. A violin supporting pad curved to conform to and adapted to rest upon the shoulder strips extending laterally from said pad and arranged to be folded respectively back 35 over the edge of the outer garment of the user above said shoulder pad to provide a protective covering, and inwardly beneath

the user's inner garment to form retaining means.

2. A violin supporting pad having a concave inner surface and a pair of strips of flexible material projecting laterally from one side of said pad, one of said strips being adapted to coöperate with the clothing of the player to retain the pad in position on the shoulder, and the other strip being adapted to form a protective covering for the garment immediately over the pad when the same is applied for use. 40

3. A violin supporting pad having a concave inner surface gradually decreasing in thickness from top to bottom, and a pair of strips of flexible material projecting laterally from one side of said pad, one of said strips being adapted to coöperate with the clothing of the player to retain the pad in position on the shoulder, and the other strip being adapted to form a protective covering for the garment immediately over the pad when the same is applied for use. 45

4. A device of the class described, comprising a pad adapted to be positioned on the shoulder beneath the collar portion of a garment and a pair of strips of flexible material projecting from one edge of said pad, one of which strips is adapted to be positioned beneath a portion of the player's garment to retain the pad in position and the other strip is adapted to form a protective covering for the garment immediately over 70 said pad. 60

In testimony whereof I have signed my name to this specification.

HENRY F. FISHER.
